PRINTING MACHINE

Franklin E. Curtis, Euclid, Ohio, assignor to Addressograph-Multigraph Corporation, Wilmington, Del., a corporation of Delaware

Application November 16, 1940, Serial No. 365,853

14 Claims. (Cl. 101—58)

This invention relates to printing machines of the kind through which printing devices are sequentially fed to have impressions made therefrom onto sheets successively passed through the machine.

While a wide variety of printing devices are sequentially fed through printing machines of the character to which this invention pertains, that shown in Gollwitzer Patent No. 2,049,436, patented August 4, 1936, is exemplary. As is well understood in the art, printing devices of this general character have heretofore been fed into printing position in the printing machine to have one or more impressions made therefrom onto each sheet passed through the machine, and where more than one impression was to be made from each printing device onto each sheet, multiplicating means have been incorporated in the machine that were effective to interrupt operation of the means which feed the printing devices through the machine until the desired number of impressions had been made from a particular printing device onto a particular sheet, after which the printing device feeding means were again rendered operative and a new printing device was then fed into printing position. Multiplicating means of this general nature are disclosed, for example, in Gollwitzer Patent No. 2,002,771, patented May 28, 1935.

In other printing machines of this general character as, for example, those employed to address magazines and the like and wherein it was desired to assure that each magazine or other sheet to be printed received an address from a particular printing device, means were incorporated in the machine for interrupting operation of both the means operative to feed the printing devices and the means operative to feed the sheets, one such arrangement for this purpose being disclosed in Duncan and Hubbard Patent No. 1,952,914, patented March 27, 1934.

There have been other arrangements to which resort has been had to control operation of the means which feed the printing devices through the printing machine sequentially and in a step-by-step manner, but in each such instance heretofore the means operative to so feed the printing devices through the machine were normally operative, which is to say, multiplicating or other means which brought about either temporary or permanent interruption of operation of the printing device feeding means functioned to render such means inoperative, for in the absence of the operation of such means the printing device feeding means continued to operate to feed printing

devices through the machine so long as the machine remained in operation.

However, there are instances where it is desirable to make a large number of impressions from each printing device fed into printing position and this, of course, entails maintaining the printing device in printing position until the desired number of impressions have been made therefrom. In such an instance the means for feeding the printing devices may be advantageously arranged to normally be inoperative so that such means will be rendered effective to advance the printing devices only when it is desired to move a printing device from printing position and to bring another printing device into printing position, and so to do constitutes an important object of the present invention.

One example of an instance where it is desirable to make a relatively large number of impressions from each printing device fed into printing position is where business instruments of the kind described in the co-pending application of Harold M. Whittlesey, Serial No. 403,357, filed July 21, 1941, are being prepared in accordance with the method of preparing such instruments described in that application. It will be understood, however, that there are other instances where a printing device will advantageously be retained in printing position while a relatively large number of impressions are being made therefrom and that there are other circumstances where it will be advantageous to control the advance of the printing devices through the machine so that the advancing means will need not be kept normally operative. In such instances, however, usually a different number of sheets or the like may be fed through the machine to receive one or more impressions from the different printing devices moved into printing position, and hence in such instances a particular printing device should be moved from printing position and another printing device substituted therefor only after all of the sheets or the like that are to receive impressions from the particular printing device disposed in printing position have had such impressions made thereon. Thus, in such instances it is advantageous to control the advancing of printing and like devices through printing machines of the aforesaid character from the sheets, or better, characteristics selectively included in the sheets, passed through the machine, and so to do is yet another important object of this invention.

In an instance where a collection of sheets or the like are fed through a printing machine and

each is to receive impressions from the same printing device, it is often necessary to make a plurality of impressions from such a printing device on each sheet fed through the machine, and yet another object of this invention is to enable this to be accomplished when the need so to do arises, and an object ancillary to the foregoing is to employ means effective to position each sheet fed into a printing machine relative to a printing device disposed at printing position therein and to so arrange such means that a plurality of different positions on each sheet may be arranged relative to printing position whereby a plurality of spaced impressions may be made on each sheet.

Other and more specific objects are to maintain a driving member in a means for feeding printing and like devices through a printing machine out of driving connection with a driven means included with such feeding means until it is desired to impart advancing movement to the printing and like devices to be fed through the machine; to control interconnection between the driving and driven means in a means for feeding printing and like devices through a printing machine under characteristics selectively included in sheets or the like passed through the machine; to latch means effective to prevent driving connection between a driving and a driven member in a means for feeding printing and like devices through a printing machine in such a position that driving connection between the driven and driving members will normally be prevented; to unlatch means of the aforesaid character under control of a detecting means included in the machine responsive, for example, to characteristics selectively included in sheets or the like successively fed through the machine; to insure against undesired successive feeding of printing and like devices by restoring to effective position, in each feeding operation of a printing device feeding means, means effective to prevent a feeding operation of the printing or like device feeding means; to electrically control means operative to maintain a driving member of a printing or like device feeding means disconnected from a driven member in such means; and to enable means effective to prevent successive feeding of printing or like devices to be readily rendered ineffective when so desired.

In those instances where the advance of printing or like devices through a printing machine is under control of detecting means responsive to sheets, or characteristics included in sheets, passed through such a printing machine, and particularly where the sheets are automatically fed into printing position in the machine, it is important that machine operation, and particularly operation of the printing or like device advancing means, be interrupted if a sheet should not be fed, and yet another object of this invention is to prevent such operation or operations in the event no sheet or the like is fed; and other objects are to interrupt machine operation after normally inoperative means for advancing printing or like devices have functioned to advance such devices; and to utilize common means for interrupting machine operation upon failure of a sheet to feed or after an operation of normally inoperative printing or like device advancing means.

Other and further objects of the present invention will be apparent from the following description and claims and are illustrated in the accompanying drawings which, by way of illus-

tration, show a preferred embodiment and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claims.

In the drawings,

Fig. 1 is a plan view of a printing machine of the general character with which my invention may be utilized and in which my invention is incorporated;

Fig. 2 is a front elevation of the machine shown in Fig. 1;

Fig. 3 is a vertical sectional detail view taken substantially on the line 3-3 on Fig. 2;

Fig. 4 is a sectional detail view taken substantially on the line 4-4 on Fig. 3;

Fig. 5 is a vertical sectional detail view taken substantially on the line 5-5 on Fig. 2;

Fig. 6 is a fragmentary detail view of certain of the parts illustrated in Fig. 3 and in which certain of the operative parts are shown in one operative position thereof;

Fig. 7 is another fragmentary view of the parts as shown in Fig. 3 and showing certain of the operative parts in another of the operative positions thereof;

Fig. 8 is a sectional view taken substantially on the line 8-8 on Fig. 3;

Fig. 9 is a detail view taken substantially on the line 9-9 on Fig. 1;

Fig. 10 is a transverse sectional detail view taken substantially on the line 10-10 on Fig. 9;

Fig. 11 is a longitudinal sectional view through the printing device feeding means;

Fig. 12 is a fragmentary view of a portion of the parts shown in Fig. 9 but showing these parts in another operative position;

Fig. 13 is an elevational view of a control sheet utilized in the machine illustrated and described herein;

Fig. 14 is a detail view taken substantially on the line 14-14 on Fig. 9;

Fig. 15 is a detail view taken substantially on the line 15-15 on Fig. 1;

Fig. 16 is a view looking in at the right-hand side of Fig. 15; and

Fig. 17 is a view, similar to Fig. 15, showing certain of the operative parts in another operative position.

As will be apparent from the following description, the present invention primarily pertains to a control for the means operative to feed printing and like devices through a printing machine, and in view of this it will be understood that while I have shown a particular type of printing machine in the accompanying drawings and will hereinafter describe the structural characteristics of this machine, my invention may well be utilized to control the printing or like device feeding means of a wide variety of other machines.

The machine disclosed in the accompanying drawings is of the general character of that disclosed in Gollwitzer Patent No. 2,002,773, patented May 28, 1935, which, as shown in the accompanying drawings, includes a stand 20 for supporting a bed plate 21 in spaced relation with the floor or other support. Uprights as 22 extend upwardly from the bed plate 21 and along with brackets 23 and 24 support bearings in which 75 driving, cam and other shafts included in the

machine are journaled, these uprights and brackets including suitable pads and sub-brackets on which other machine parts, such as the table top 25, are mounted.

Shafts as 26 and 27 are suitably journaled at opposite ends of the table top 25 and pulleys as 28 and 29 are fast on these shafts to have endless feed tapes T passed thereabout, the passes of the tapes T between the pulleys 28 and 29 extending across the table top 25 and being effective to carry sheets deposited thereon into printing position in the machine beneath the platen P. As best shown in Fig. 2, the tapes T are passed about take-up rollers 30 and 31 respectively carried by arms 32 and 33 supported by brackets 34 and 35 which are, in turn, carried by the frame 20 and the bed plate 21. In order to insure synchronous operation of the shafts 26 and 27 and therefore the pulleys 28 and 29, other pulleys 36 and 37 are respectively fast on the shafts 26 and 27, and an endless driving belt 38 is passed about these pulleys and take-up pulleys similar to and supported in a similar manner to the take-up pulleys 30 and 31.

In the present instance a rack 39 is provided at the right-hand end of the machine, as it is viewed in Figs. 1 and 2, and the sheets S that are to be printed in the machine are stacked therein. Suitable means are provided for withdrawing the sheets one at a time from the rack 39 and for depositing the sheets on the tapes T, as they pass about the pulleys 29, typical means for this purpose being disclosed in the aforesaid Gollwitzer Patent No. 2,002,773. The means which are effective to withdraw the sheets S from the rack 39 in the present instance are those which are described in detail in the aforesaid Gollwitzer patent, and it is to be understood that the other suitable means might be employed in place of the illustrated means without departing from the purview of this invention. However, such means include suction nozzles as 40 which are moved into engagement with the innermost sheet in the stack thereof in the rack 39, and these nozzles are thereafter rocked so as to bring the upper edge of this innermost sheet over into engagement with feed rollers as 41 mounted on the driven shaft 42, the cooperating clamping rollers as 43 mounted on the shaft 44 being withdrawn from sheet clamping cooperation with the rollers 41 at the time the nozzles as 40 are rocked to bring the sheet over onto the feed rollers. However, under control of means described in detail in the aforesaid Gollwitzer patent, the rollers 43 are moved into position to clamp a sheet brought into engagement with the rollers 41 against such rollers and thereupon the sheet is fed forwardly onto the tapes T above the pulley 29 to thereafter be deposited on the tapes and be carried thereby into printing position in the machine in a manner described in full detail hereinafter.

A magazine M extends upwardly from the table top 25 about midway in the extent and along the rear edge thereof and in the manner well understood in the art the printing or like devices D that are to be fed through the machine are introduced into this magazine so that the means for feeding the printing or like devices through the machine and into printing position beneath the platen P may successively withdraw the lowermost device D from this magazine and feed it to and from printing position.

A pair of spaced apart guides as 45 extend forwardly from the magazine and terminate in

a discharge chute C, Fig. 11, through which the printing devices pass to be collected in the galley G after they have been discharged from printing position above the anvil A beneath the platen P. A shaft 46 is suitably journaled in the frame of the machine near the front end thereof and another shaft 47 is also journaled in the frame of the machine rearwardly of the magazine M, as best shown in Fig. 11. Sprockets as 48 and 49 are respectively fast on shafts 46 and 47 and endless chains as 50 are passed about the sprockets as 49 to have the upper passes thereof disposed inwardly of the guides 45. Pawls as 51 are provided on the chains 50 to project upwardly from the passes thereof inwardly of the guides 45, the pawls 51 on the respective chains 50 being aligned one with the other, and such sets of pawls are uniformly spaced apart on the chains in an amount equal to the length of the step-by-step feeding movement that is imparted to the chains in a manner described presently. In the course of such step-by-step movement imparted to the chains 50, a pair of pawls 51 move into position behind the rearwardly disposed edge of the lowermost printing device D in the magazine M and in the course of movement of the chains 50, these pawls are effective to move such printing device forwardly between the guides 45. The anvil A is spaced forwardly from the magazine M in such an amount that in the course of the step-by-step movement imparted to the chains 50, a printing device D is brought to rest above the anvil A and beneath the platen P, an ink ribbon R in the present instance being spaced above the anvil A so that when a printing device comes to rest on the anvil, and the embossed type characters on the printing device are disposed beneath this ink ribbon, an impression may be made therefrom by the platen P. Hence, when the platen P is lowered into the printing position thereof, the type characters make an impression on a sheet S interposed between the platen and the ink ribbon.

Raising and lowering movement is imparted to the platen P and the aforesaid step-by-step movement is imparted to the chains 50 from the drive shaft 52, which receives power from the main drive shaft 53 through the bevel gear interconnection 54 between these shafts. The shaft 53 is set in motion when the clutch 55, described in detail hereinafter, is engaged to connect this shaft 53 with the pulley 57, that is rotatably mounted on shaft 53 and to which power is imparted through the belts 58 from a suitable electric motor (not shown) carried by the frame of the machine.

The platen frame 59, Fig. 5, is pivotally mounted on the frame of the machine above the table top 25, as indicated at 60, and is formed to afford supports for the rollers 61 and 62 which respectively cooperate with the conjugated cams 63 and 64 fast on a sleeve 65 that is suitably clutched or otherwise connected to the drive shaft 52. The conjugated cams 63 and 64 so cooperate with the rollers 61 and 62 that the platen arm 59 is rocked about the pivotal mounting 60 therefor to thereby move the platen into and from printing position, as hereinabove described.

As stated, the printing device advancing means is driven from the drive shaft 52. Thus, a rocker 66, Fig. 5, is pivotally mounted on the frame of the machine, as indicated at 67, and carries a pair of spaced rollers 69 and 70 that respectively cooperate with the conjugated cams

71 and 72 that are fast on the shaft 52 so that when this shaft rotates, a rocking movement is imparted to the rocker 66. Another rocker, generally indicated by 73, is pivotally mounted, as indicated at 74, beneath the table top 25 and includes an arm 75 that is suitably connected, by the interconnecting means 76, with the depending arm of the rocker 66 so that as the rocker 66 is rocked about its pivotal mounting 67, the rocker 73 is rocked about its pivotal mounting 74. The rocker 73 also includes an arm 77 at the free forward end of which a pawl or driving member 78 is pivotally mounted, as indicated at 79, a spring 80 being effective on the pawl 78 to urge it toward the pins or driven members 82 on the sprocket 49. The pins 82 are uniformly spaced one from the other on a sprocket 49 in such an amount that when the pawl 78 is retracted, in a counterclockwise direction as viewed in Fig. 5, from engagement with one of such pins, it is moved into driving relation with the succeeding of such pins, in the course of the rocking movement of the arm 77 of the rocker 73 in one direction. Then when the arm 77 moves in the opposite direction, and the pawl 78 engages such succeeding of the pins 82, a driving movement is imparted to the sprockets 49, both of which are fast to the rotatable shaft 46, and consequently the chains 50 and thereupon the printing devices D engaged by the pawls 51 are moved forwardly one step in the step-by-step movement thereof so as to, as in the manner hereinabove described, be advanced from the magazine M and eventually into printing position above the anvil A.

In printing machines of the character thus far described which, as stated hereinabove, are typical of the general class of printing machines through which printing and like devices are advanced, the driving member such as the pawl 78 included in the printing device feeding means is normally arranged for engagement with the cooperating driven member or members as the pins 82 so that in the course of operation of the machine, each time the driven member as the pawl 78 is operated, an advancing movement is imparted to the printing or like devices. Even in those instances where a multiplicating arrangement has been provided as where duplicate, triplicate or quadruplicate impressions are to be made from a printing device advanced into printing position above the anvil as A, the driving means as the pawl 78 has been arranged for cooperation with a driven member as the pins 82 each time the driving member is set in operation, for in such instances a counting or equivalent means has usually been provided to render the driving means as the pawl 78 (and of course the parts associated therewith) inoperative in alternate rotations of the shaft as 52, in the instance where duplicate impressions are to be made from each printing device fed into printing position, or to render it inoperative for two successive rotations of such shaft and then effective in the third rotation where triplicate impressions were to be made and so on where quadruplicate or even more impressions were to be made from a particular printing device fed into printing position.

However, in those instances where the number of impressions to be made from each printing device fed into printing position is such that it is advantageous to maintain a driving member as the pawl 78 disconnected from the driven member as the pins 82 in all instances except

those comparatively infrequent instances where an advancing movement is to be imparted to the printing devices, novel means, such as are now to be described, are incorporated in the machine to enable this to be accomplished.

Thus, particularly referring to Figs. 3, 4, 6, 7 and 8, it will be seen that a bracket 83 is provided on the upright 22 and includes a lug 84 on which a rocker, generally indicated by 85, is pivotally mounted, as indicated at 86. The rocker 85 includes an upwardly projecting arm 87 having a yieldable finger 88 mounted thereon that is disposed adjacent the sprocket 49 on which the pins 82 are mounted so that the finger 88 is aligned with the pawl or driving member 78.

The pawl or driving member 78 is shown in its normal at rest position in Fig. 3 but in the course of an operation of the shaft 52 and during substantially the first one hundred eighty degrees of rotation of this shaft, the pawl 78 is retracted from the position in which it is shown in Fig. 3 into the position in which it is shown in Figs. 6 and 7, and whether the pawl assumes the position shown in Fig. 6 or the position shown in Fig. 7 is determined by the position of the finger 88 and therefore, of course, the rocker 85. Normally the rocker 85 is disposed in the position shown in Figs. 3 and 6 so that when the pawl 78 attains its fully retracted position shown in Fig. 6 and is engaged with the finger 88, the pawl or driving member 78 is prevented from engaging a driven member such as a pin 82.

The rocker 85 is normally latched in the position where the finger 88 engages the pawl 78 by the engagement of the lug 89, on the depending arm 90 of the rocker 85, with a shoulder 89' on the latch arm 91. The latch arm 91 is rotatable on the shaft 92 fast in the bracket 93 carried by the upright 22. A spring 94, Figs. 3, 7 and 8, extends between a spring anchor 95 on the bracket 93 and a spring anchor 96 on the arm 90 of the rocker 85, and this spring is effective to hold the lug 89 in engagement with the shoulder 89' on the latch arm 91.

The connection between the lug 89 and the shoulder 89' is controlled by a solenoid 97 mounted on the bracket 93. This solenoid includes an attractive core 98 slotted, as indicated at 99, Fig. 4, to receive one end of an arm 100, a pin 101 extending through a slot in the arm 100 to anchor it in the slot 99. The arm 100 is pivotally mounted on the shaft 92 and a sleeve 102, disposed about the shaft, serves to interconnect the arm 100 and the latch arm 91. The latch arm 91 includes a depending arm 103. One end of a spring 104 is connected to the free end of the arm 103 and the other end of this spring is connected to a spring anchor 105 connected to the bracket 93, the anchor 105 having an opening 106 therein into which the pin 107 on the bracket 93 is extended. The spring 104 is effective through the arm 103 to urge the latch arm 91 and therefore the arm 100 and the core 98 into the upper positions thereof shown in Fig. 3 in which the shoulder 89' on the latch arm 91 engages the lug 89. The parts retain this position until the solenoid 97 is energized. When, however, the solenoid 97 is energized and the core 98 thereof is attracted downwardly, the arm 100 and the latch arm 91 are pivoted downwardly into the position shown in Fig. 7 and thereupon the rocker 85 is freed to the action of the spring 94 and is moved from the position shown in Fig. 3 into the position shown in Fig. 7. When the rocker 85 moves into this unlatched position,

shown in Fig. 7, the finger 88 is disposed out of the path of the pawl 78 which may, therefore, move into engagement with the adjacent of the pins 82 when the arm 77 of rocker 73 attains its retracted position shown in Figs. 6 and 7.

When the rocker 85 is in the latched position shown in Fig. 8, so that the finger 88 may engage the pawl 78 in the manner shown in Fig. 6 at the end of the retractive movement of the arm 77 of the rocker 73, the pawl 78 is prevented from 10 engaging the adjacent pin 82 during the restoring movement of the arm 77 from the position shown in Fig. 6 back into the position shown in Fig. 3 and, as a result, the pawl or driving member 78 does not impart driving movement to the 15 adjacent pin 82 and consequently the sprocket 49 and the chains 50 or, in other words, the driven member of the printing device feeding means. However, when the rocker 88 attains its unlatched position, described hereinabove and shown in 20 Fig. 7, the finger 88 cannot engage the pawl 78. Hence, the pawl 78 moves into driving relation with an adjacent pin 82, as shown in Fig. 7. Then during the restoring movement of the arm 77, from the position shown in Figs. 6 and 7 back 25 into the position shown in Fig. 3, driving movement is imparted to the adjacent pin 82 and therefore the sprocket 49 on which it is mounted and the chain passed about this sprocket. Since the two sprockets 49 are both fast to shaft 46, this driving movement is imparted to sprockets 49 and both chains 50 which, through the pawls 51 thereon, impart an advancing movement to the printing devices D. Such an advancing movement of the printing devices D occurs, however, only when 30 the rocker arm 85 is in its unlatched position, such as shown in Fig. 7, and in the normal operation of the machine this occurs only when the solenoid 97 is energized.

It has been explained hereinabove that where a plurality of sheets as S are to receive impressions from a printing device D disposed in printing position in the machine, it is advantageous and desirable to control the advancing of the printing devices through the machine by the sheets or, more particularly, by characteristics included in selected of the sheets. It is to be understood, however, that while this is an advantageous way of bringing about energization of the solenoid 97 and therefore, in the present instance, advancing of the printing devices, resort could be had to some other arrangement for bringing about this energization or, in other words, for bringing about an advancing movement of printing or like devices at a selected or desired time.

However, in the illustrated form of the invention, energization of the solenoid 97 is brought about under the characteristics of a sheet of the kind illustrated in Fig. 12. To this end detecting means are provided in the machine which are responsive to characteristics incorporated in a sheet such as that shown in Fig. 12 and which is indicated by SP. The sheet SP, which is substantially rectangular in outline as are the other sheets to be printed in the machine, has a longitudinally extending slot 103 formed therein which is preferably centrally located in the sheet SP but which, in any event, is so located in the sheet that it will not lie in the path of a suction nozzle as 49 that is adapted to withdraw sheets from the rack 39.

After the sheets are withdrawn from the rack 39 and deposited on the feed rollers 41 to be fed by the feed tapes T, the sheets pass beneath a

detecting wheel 109 that is carried by a shaft 110 in alignment with the peripheral groove 111 in the wheel 112 fast on the shaft 21. A lug 113, Fig. 10, depends from the frame of the machine above the table top 25 and carries a stud 114 on which the arm 116 of a rocker, generally indicated by 117, is pivotally mounted, the shaft 110 being suitably fast in the rocker 117. The rocker 117 includes an arm 118 that extends at an angle upwardly from the arm 116 thereof. The arm 118 has a cam follower roller 119 mounted at the free end thereof which normally rides on the periphery of the cam 120 so that the rocker 117 and therefore the shaft 110 and detecting wheel 109 are held in an upper position. The cam 120 has a drop 121 in the periphery thereof and is mounted on a cam shaft 122. In a manner to be explained presently, the cam shaft 122 is operated in timed relation with the means which withdraw sheets from the rack 39 and feed them to the feed tapes T. Hence, at a predetermined time in the course of operation, the drop 121 moves into position beneath the roller 119 and thereupon the detecting wheel 109 is free to move downwardly and perform a detecting operation.

The timing and arrangement is such that a sheet, fed by the rollers 41, should be disposed between the wheel 109 and the groove 111 in the wheel 112 at the time the drop 121 in cam 122 moves into alignment with the roller 119. If the wheel 109 engages a sheet S at this time, the rocker 117 is prevented from pivoting and the roller 119 does not move into the drop 121. However, when the wheel 109 does not engage the face of a sheet S, or moves into an opening 108 in a sheet SP, the rocker 117 pivots downwardly since the wheel 109 will, in these circumstances, pass into the groove 111 in the wheel 112. When the rocker 117 so pivots downwardly, the roller 119 passes into the drop 121 in the cam 120 for a purpose to be explained hereinafter. Thus, so long as sheets S are fed beneath the wheel 109, this roller and the rocker 117 are maintained in an upper position, but when a sheet SP having an opening 108 therein moves below the wheel 109, these parts move into a lower position. The present machine is so arranged that whenever the wheel 109 attains such a lower position by reason of the presence of a sheet SP therebelow, the solenoid 97 is to be energized so as to unlatch the rocker 85 to permit it to assume the position shown in Fig. 7. This is accomplished by associating a switch with the wheel 109 which is closed when the wheel 109 attains the aforesaid lower position. The wheel 109 may also attain this lower position in the event no sheet lies therebelow. This affords a safety arrangement described in detail hereinafter.

As to the switch which is closed when detecting wheel 109 attains its lower position, it will be noted that a finger 123 projects forwardly from the free end of the shaft 110, on which wheel 109 is mounted. The finger 123 carries an adjustable screw 124 at the free end thereof that is disposed above the free end of a spring contact 125 having a contact point 126 near the free end thereof that is normally spaced away from the contact point 127 on the contact finger 128. A plate of insulating material 129 is mounted on the top of the bed plate 25 and the contact finger 128 is rested on this plate of insulating material. Bushings of insulating material as 130 are disposed between the contact fingers 125 and 128, screws 131 serving to anchor the insulating plate 129,

the contacts 128 and 125 and the bushings 130 in position with the contacts 125 and 128 electrically insulated one from the other.

A conductor 132, Figs. 9 and 3, leads from the spring contact 125 to one end of the winding of the solenoid 97 and a conductor 133 leads from the other end of this winding to a suitable source of electric current (not shown), a conductor 134 leading from this source of current to the contact 128. Whenever the detecting wheel 109 attains its aforesaid lower position, the adjusting screw 124 forces the contact point 126 into engagement with the contact point 127 and thereupon circuit is closed to the winding of the solenoid 97 and as an incident to the resulting energization of the solenoid 97, the core 98 thereof is attracted, against the effect of the spring 104, from the upper position shown in Fig. 3 into the lower position shown in Fig. 7. Thereupon the shoulder 89' is withdrawn from engagement with the lug 89 and the rocker 85 is freed to the effect of the spring 94 to thereby be disposed in the position shown in Fig. 7 wherein the finger 88 is held out of the path of the driving member or pawl 78.

Such energization of the solenoid 97 and retraction of the finger 88 from the position in which it may engage the pawl 78 is timed to occur during the time the pawl 78 is moving from the position in which it is shown in Fig. 3 into the retracted position thereof shown in Figs. 6 and 7. It will be understood that if a normal sheet S is disposed beneath the wheel 109 at the time the drop 121 moves in position below the roller 119, then the solenoid 97 is not energized with the result that the finger 88 engages the pawl 78 and maintains it in the position shown in Fig. 6 to prevent driving movement being imparted to the sprockets 49 and the chains 50. When, however, by reason of the presence of a sheet SP, therebelow, the detecting wheel 109 moves into its aforesaid lower position and circuit is closed to the solenoid 97 and, as explained above, the finger 88 is held from contact with the pawl 78, then at the end of its retracting movement the pawl 78 attains the position shown in Fig. 7 so that in the course of the return of the arm 77 of the rocker 13 to its normal at rest position shown in Fig. 3, the driving member or pawl 78 is effective on the driven member, including the adjacent pin 82 and the sprocket 49, to thereby impart an advancing movement to the chains 50. Thereupon the pawls as 51 on these chains are effective to withdraw the printing device D that has been disposed in printing position above the anvil A from this position and to advance it to the discharge chute C whereby this printing device will pass into the galley G, and the pawls 51 are also effective to advance the succeeding or a new printing device into printing position above the anvil A beneath the platen P.

Thus, at least each time a card as SP having an opening therein as 108 moves into position beneath the detecting wheel 109, circuit is closed to the solenoid 97 and the rocker 85 is freed to the action of the spring 94 so that the finger 88 moves into a position, such as that shown in Fig. 7, wherein it is prevented from engaging the driving member as the pawl 78 so that this driving member is permitted to engage a driven member as a pin 82 and thereby bring about an advancing movement of the printing or like devices. It will therefore be seen that, under control of the sheets or, as in the present instance, characteristics included in selected of the sheets that are fed through a printing machine, an ad-

vancing movement is imparted to the printing devices or, in other words, the advancing of the printing devices is under control of the sheets.

As will be explained in greater detail hereinafter, there may be instances where two special sheets as SP including characteristics under control of which an advancing movement is imparted to the printing devices may pass through the machine successively, and it will be recognized that in such an instance an advancing movement should be imparted to the printing or like devices in successive operations of the machine. In other instances, of course, other sheets will be interposed between successive sheets as SP and in such instances a sheet that is adapted to receive impressions from the printing device that has moved into printing position will follow a special sheet as SP which brings about the advancing of a printing device into printing position. Furthermore, usually a number of sheets will be interposed between special sheets as SP and all of the sheets interposed between special sheets as SP, that is, sheets which include the characteristics which bring about advancing of the printing devices, are to receive impressions from the same printing device.

Hence, it is desirable that the means, in the present instance the finger 88, which controls the interconnection between a driving and a driven member in a means for advancing printing devices through a printing machine, be restored to position once it has been retracted from such position in order that driving connection between the driving and driven means, as aforesaid, will be established only when desired. Furthermore, in order to prevent undesired advancing of the printing devices, it is advantageous to insure that the means which are operative to maintain a driving means disconnected from a driven means be maintained in or restored to the position in which this will be effected as an incident to each complete cycle of operation of the machine.

In the present instance this is accomplished by insuring that the rocker 85, and therefore the finger 88, is restored to or maintained in the position shown in Figs. 3 and 6, in which it is effective to prevent driving connection between the driving and driven means, as an incident to the completion of a cycle of operation of the machine, and the arrangement by which this is accomplished will now be described.

A cam shaft 135, journaled in bearings as 136 suitably supported from the frame of the machine, is provided and functions to control certain operations of the machine, as will be explained presently, this cam shaft being driven from the main drive shaft 52 in a manner also explained presently. Furthermore, since the present machine is arranged to make three impressions on each sheet fed through the machine that is to receive impressions, the cam shaft 135 makes one revolution to three of the drive shaft 52 from which, as explained hereinabove, the platten arm 59 and the driving rocker 13 of the printing device advancing means are operated. Thus, the cam shaft 135 makes one complete revolution for each sheet that is passed through the machine and may therefore advantageously be employed to insure, in the present instance, restoration of the rocker 85 to its latched position.

To this end a cam 137, Figs. 3 and 4, is fast on the drive shaft 135 and is engaged with a cam follower roller 138 rotatably mounted on the bell

crank lever, generally indicated by 139. The bell crank lever 139 includes an arm 140 that extends across the top of the table 25 from the rear edge thereof, as best shown in Fig. 3, and the free end of this arm 140 is pivotally mounted, as indicated at 141, on a bracket 142 fast to the table top 25, being bolted thereto as indicated at 143. The other arm 144 of the bell crank lever 139 depends through a slot 145 in the table top 25 and one end of an adjustable link 146 is pivotally connected to the free end thereof, as indicated at 147.

A handle 148 projects forwardly from the arm 90 of the rocker 85 and has a boss 149 formed therein to which one end of an arm 150 is fast, as indicated at 151. As best shown in Figs. 4 and 8, the spring anchor 96 is in the form of a bolt, which includes an enlarged head that constitutes the aforesaid lug 89, and that portion of the spring anchor 96 inwardly of the head or lug 89 extends through a suitable opening in the lower end of the arm 90 and also through an adjacent portion of the arm 150, a nut 151 serving to draw the inner end of the lug 89 into engagement with the adjacent face of the arm 90 and to clamp the arm 150 to the arm 90. Thus, it will be seen that the arm 150 is firmly connected to the lower end of the arm 90 and to the handle 148 and therefore this arm is rigidly connected with the rocker 85. A pin 152, Figs. 3, 4 and 7, is fast in the end of the arm 150 opposite that connected to the boss 149 and extends through a slot 153 formed in the lower end of a bar 146a of the link 146. A spring anchor 154 is fast in the lower end of the bar 146a and a spring 155 extends between this spring anchor and the pin 152, the spring 155 acting on the link 146, the spring 155 being effective on the link 146 to urge the cam follower roller 138 toward the cam 137, as best shown in Fig. 3.

The cam 137 includes a rise and when the parts attain their normal at rest position, shown in Fig. 3, at the end of a complete rotation of the cam shaft 135, the cam follower roller 138 is engaged with the rise on the cam 137. This is effective through the bell crank 139 to urge the link 146 into a downward position in which the upper end of the slot 153 seats on the pin 152 in the arm 150, and the arrangement is such that when this occurs the arm 150, and therefore the rocker 85 to which it is firmly connected, is disposed in the position shown in Fig. 3, wherein the lug 89 is arranged in such position that the spring 154 may act to bring the shoulder 89' on the arm 90 into latching engagement with the lug. Thus each time the cam shaft 135 returns to its normal at rest position, the cam 137 is effective to restore the lug 89 on the arm 90 of the rocker 85 to its latched position, if the lug 89 has been unlatched from the shoulder 89' or, in the event such unlatching has not occurred, this arrangement is effective to insure that the rocker 85 is retained in its latched position.

It is important that the cam 137 insure return of the lug 89 to latched position and since this entails engagement of the upper end of the slot 153 with the pin 152, it will be manifest that the length of the link 146 is important. For this reason the link 146 includes bars 146a and 146b. As best shown in Fig. 3, the bar 146a has a slot 158 therein while spaced openings 157, Fig. 4, are provided in the bar 146b. Bolts 159 are passed through the slot 158 and the openings 157 and then by sliding the bar 146a relative to the bar 146b and thereafter tightening the nuts 159, the

length of the link 146 may be adjusted to insure that when the rise on the cam 137 is in engagement with the cam follower 138, the lug 89 will be disposed in position to be engaged with the shoulder 89' on the arm 90.

Sheet positioning and kindred means are provided in the machine and to this end a frame F, Figs. 1 and 2, is suitably supported above the table top 25 and includes a rod 160 having bushings as 161 secured thereto in adjusted positions therealong. Roller supports as 162 carrying rollers as 163 are pivotally connected to the bushings as 161 and support the rollers as 163 in position above one of the feed tapes T, as best shown in Fig. 1. The most right-hand of the rollers 163, as viewed in Fig. 1, is mounted in such a position that the leading edge of a sheet advanced to the feed tapes T by the feed rollers as 41 moves onto the tapes T and below the roller 163 prior to the time the trailing end of the sheet moves from the bite between the clamping rollers as 43 and the feed rollers as 41, and by this time the side edges of the sheet are embraced between the sides of the sheet guideway 164, Figs. 1, 3 and 6, and at this time the aforesaid most right-hand roller 163 is effective to clamp the sheet down onto the underlying tape T. When this occurs, by reason of the fact that the sheet is effectively guided by the sheet guideway 164, the sheet is thereafter fed along by the feed tapes T.

In the present instance a sheet which moves beneath the roller 163 advances into engagement with a stop finger 167 carried by a shaft 168 pivotally mounted in the frame F. The shaft 168 includes a finger 169 carrying a roller 170 which cooperates with the face cam 171 fast on the cam shaft 135 and so long as the roller 169 is engaged with the rise on the face cam 171, the shaft 168 is disposed in such a position that the stop finger 167 is lowered into sheet stopping position. At a predetermined time in the rotation of the cam shaft 135, the drop in the face cam 171 moves into association with the roller 170 and thereupon the stop finger 167 is pivoted from sheet stopping position and thereupon the sheet which has been engaged therewith is advanced by the feed tapes T into engagement with the succeeding stop finger 172, and at this time the sheet moves beneath the succeeding roller 163 to be held thereby in engagement with the feed tapes T.

The cam 171 is so arranged on the cam 135 that it serves to maintain the stop finger 167 in sheet stopping position during the time a sheet is being fed past the detecting wheel 169 by the feed rollers as 41, and furthermore the cam 171 is so arranged that it retains the stop finger 167 in sheet stopping position until the platen P has operated to make an impression onto a sheet engaged with this stop finger from the printing device disposed on the anvil A. However, after an impression has been made by the platen P onto a sheet engaged with the stop finger 167, the drop on the cam 171 moves into association with the roller 170 to thereby elevate the stop finger 167 and thereupon, as stated, the sheet moves forwardly into engagement with the stop finger 172.

The stop finger 172 is mounted on a shaft 173 and includes an arm 174 having a roller 175 thereon that is engageable with the cam 176 also fast on the cam shaft 135. The cam 176 serves to maintain the stop finger 172 in sheet stopping position until after the platen P has made another or second impression on the sheet

S. It will be manifest, however, that since the sheet has advanced from engagement with the stop finger 167 into engagement with the stop finger 172, the impression made on the sheet S at the time the leading edge thereof is engaged with the stop finger 172 will be spaced on the sheet away from the impression made by the platen P during the time the sheet was engaged with the stop finger 167.

Likewise, after the platen P has functioned to make an impression on a sheet having the leading edge thereof engaged with the stop finger 172, the cam 176 functions to elevate this stop finger from stopping position, but at this time the cam 171, similar to the cams 176 and 171, acts to lower the stop finger 173 (that is under control of the cam 171 in the same manner as that in which the stop fingers 172 and 167 are respectively under control of the cams 176 and 171) into sheet stopping position. Then during the time the leading edge of the sheet is engaged with the stop finger 173, the platen P functions to make still another or third impression on the sheet which, since the sheet has advanced from engagement with the stop finger 172 into engagement with the stop finger 173, will be spaced from two impressions previously made on the sheet. After the platen P has functioned to make this third impression on the sheet, at which time the sheet will be below the most left-hand of the rollers 163, the cam 171 functions to raise the stop finger 173 and thereupon the sheet moves forwardly into the bite between the sheet discharging rollers 179 and the tapes T and passes into the sheet collector K.

Thus, it will be seen that in the present instance three stop fingers are provided and the leading edge of a sheet carried along by the feed tapes T successively moves into engagement with these stop fingers to thereby bring spaced positions on the sheet into position below the platen P, whereby three impressions are made by the platen onto the sheet at spaced intervals from a printing device disposed on the anvil A. It will be understood, however, that a greater or less number of stop fingers might be provided so that a greater or less number of impressions might be made on each sheet fed into the machine without departing from the purview of the present invention. It will also be understood that the stop fingers are so supported on the frame F and that the cams as 171 are so fast to the cam shaft as 135 that these parts may be moved into adjusted positions so that the impressions may be made on the sheets at desired positions as, for example, in registration with other data or the like appearing on the sheets.

It will thus be seen that once the machine is set in operation and a printing device has been advanced into printing position impressions will be made at spaced intervals on sheets successively fed into the machine until a special sheet as SP moves into position beneath the detecting wheel 109. When, however, a special sheet as SP moves beneath the detecting wheel 109, an advancing movement is imparted to the printing devices, as hereinabove described, and subsequent to the time a leading edge of such sheet moves into engagement with the first stop finger 167, the new printing device will be disposed in printing position. The arrangement is such, however, that an impression is not made from the printing device newly disposed in printing position at this time for the conjugated cams which reciprocate the platen are so arranged on the sleeve

65 and relative to the shaft 52 that the platen is lowered into printing position during the first one hundred eighty degrees of rotation in a particular rotation of the shaft 52 or, in other words, as an incident to the first part of a cycle of operation.

In many instances it is desirable, when a new printing device is advanced into printing position, that operation of the machine be interrupted. Therefore, in the present instance, when a special sheet as SP moves beneath the detecting wheel 109 and thereafter the leading edge of this sheet moves into engagement with the stop finger 167, operation of the machine is interrupted.

Moreover, if for any reason a sheet should not be fed by the rollers as 41 at a time when such a sheet should be fed, then in the course of operation of the machine the detecting wheel 109 will be free to move into the groove 111 and in an instance such as this it is desirable that operation of the machine be interrupted.

It will be recalled that the rocker 117 which carries the shaft 110 on which the detecting wheel 109 has been described as moving into a lower position each time the detecting wheel 109 moves into the groove 111, either because this detecting wheel passes through an opening as 108 in a special sheet as SP or when a sheet is not fed by the rollers as 41. In either such an instance the detecting wheel 109 may move into the groove 111 for at such a time the drop 121 in the cam 120 moves into position beneath the roller 109. In the present instance means responsive to movement of the rocker 117 into its aforesaid lower position bring about interruption of operation of the machine when this occurs as will now be described.

It has been explained hereinabove that the clutch, generally indicated by 55, Figs. 1, 15 and 16, is effective to connect the driving pulley 57 to the shaft 53 and that power for operating the machine is supplied to the driving pulley 57 which is rotatably mounted on the shaft 53. As best shown in Figs. 15 and 16, the pulley 57 includes a hub 180 that extends to a circular plate 181 fast on the shaft 53 and which includes a boss 182, Fig. 15, on which a dog, generally indicated by 183, is pivotally mounted. The dog 183 includes a nose 184 that is urged toward the periphery of the hub 180 by a spring 185 that extends between a spring anchor on the dog and a spring anchor on the plate 181. The hub 180 has a notch 186 therein into which the nose 184 may seat to thereby interconnect the plate 181 and therefore the shaft 53 to the driving pulley 57 and so long as the nose 184 remains seated in the notch 186, the shaft 53 rotates with the pulley 57.

An arcuate arm 187 is pivotally mounted on the machine frame, as indicated at 188, and has a boss 189 thereon near the free end thereof in which a pin 190 is mounted, and this pin extends into an arcuate slot 191 in the plate 192. The plate 192 is fast to a shaft 193 that is journaled in the frame of the machine and which, as best shown in Fig. 1, extends forwardly from the plate 192 through the depending lug 113, Fig. 10, to a position adjacent the detecting wheel 109 where a sleeve 194, including a unitary handle 195, is fast thereon. A spring 196 extends between a spring anchor 197 on the frame of the machine and a spring anchor 198 on the plate 192 and normally tends to urge the plate 192 into the position in which it is shown in Fig. 17 to thereby engage the pin 190 with the left-hand end of the arcuate slot 191, as it is viewed in

Figs. 15 and 17, with the pin 190 to thereby pivot the arcuate arm 187 about its pivotal mounting 198 into such position that it lies in the path of the tail of the dog 183 so that in the course of rotation of the dog 183 with the plate 181 the tail 199 moves onto the inner arcuate surface of the arm 187, and thereupon the dog 183 is so pivoted that the nose 184 is withdrawn from the notch 186 and in this way the plate 181, and therefore the shaft 53, is disconnected from the hub 180 and the driving pulley 57.

When, however, the handle 195 is grasped and moved from the position in which it is shown in Fig. 17 into the position in which it is shown in Fig. 15 and, for example, Fig. 9, the shaft 193 is rotated as is the plate 192, and the pin 190 passes through the arcuate slot 191 whereupon the arcuate surface of the arcuate arm 187 moves out of the path of the tail 199 of the dog 183 and thereupon the dog is freed to the action of the spring 185 and the nose reenters the notch 186 to thereupon again interconnect the driving pulley 57 and the shaft 53.

Inasmuch as it is desirable to maintain the machine in operation, means are provided for holding the handle 195 in the position in which it is shown in Figs. 9 and 15 to thereby dispose the plate 192 and the arcuate arm 187 in the positions in which these parts are shown in Fig. 15 so that the nose 184 may remain seated in the notch 186 to maintain the shaft 53 connected to the driving pulley 57. To this end a pad 200, providing a shoulder 201, is formed on the sleeve 194 and the shoulder 201 is engageable with a shoulder 202 on a plate 203 pivotally mounted on the depending lug 113, as indicated at 204. A finger 205 depends from the plate 203 and a spring 206 extends between a spring anchor on this finger and a spring anchor on the lug 113 and urges the plate 203 about its pivotal mounting 204 to maintain the shoulder 202 in engagement with the shoulder 201. It is the engagement of these shoulders that holds the handle 195 and, therefore, the shaft 193 and consequently the plate 192 and the slot 191 therein in Fig. 15 for the purpose explained above. A lever 207 is pivotally mounted on the frame of the machine, as indicated at 208, and has the end 209 thereof aligned with the boss 210 formed on the plate 203 and when it is desired to manually interrupt operation of the machine, the lever 207 is grasped and rocked about its pivotal mounting 208 to thereby move the lever end 209 into engagement with the boss 210 to thereby pivot the shoulder 202 out of the position in which it is shown in Fig. 9 in engagement with the shoulder 201 into a position substantially like that in which it is shown in Fig. 12 so that the shaft 193 and the parts carried thereby are freed to the action of the spring 196 whereupon the plate 192 and the arm 187 are moved into the positions shown in Fig. 17 with the effect of withdrawing the nose 184 from the notch 186 and thereby disconnecting the shaft 53 from the driving pulley 57 to interrupt operation of the machine. When the shoulder 201 is withdrawn from engagement with the shoulder 202 and the parts move into the position shown in Fig. 12, the spring 206 urges the adjacent edge of the plate 203 into engagement with the periphery of the pad 200 and in this way the clutch, generally identified as 55, and which includes the nose 184 and the notch 186 is maintained disengaged.

As has been explained hereinabove, operation

of the machine is to be automatically interrupted whenever the detecting wheel 109 passes into the groove 111 either by moving through an opening as 108 in a special sheet SP or when a sheet 5 is not fed between the detecting wheel 109 and the periphery of the wheel 112 in which the groove 111 is afforded. To this end a rod 211, Figs. 9, 12 and 14, has an inturned end 212, Fig. 14, that extends into the boss 210 on the plate 203, and this rod is passed through an opening 213 in the lug 214 on the rocker 117 and the free end of the rod 211 beyond the lug 214 is formed to afford a shoulder 215, Fig. 9. As best shown in Figs. 9, 12 and 14, a cam 216 is fast on the cam shaft 22 in alignment with the shouldered end 215 of the rod 211, and this cam is cut away to provide a shoulder 217.

So long as the roller 119 rides on the periphery of the cam 120 or when the drop 121 in the cam 120 moves beneath the roller 119 to thereby permit the detecting wheel 109 to drop onto a sheet disposed in the bite between the wheel 109 and the wheel 112, the rocker 117, as explained hereinabove, is maintained in an upper position. So long as the rocker 117 is maintained in this upper position, the rod 211 and particularly the shouldered end thereof is held out of the path of the shoulder 217 on the cam 216 by reason of the extension of the rod 211 through the opening 213 in the lug 214 on the rocker 117. When, however, the drop 121 in the cam 120 moves beneath the roller 119 to thereby permit the detecting wheel 109 to lower and no sheet is disposed in the bite between this detecting wheel and the cooperating wheel 112 or when an opening as 108 in a special sheet as SP is disposed beneath the wheel 109 and this wheel, and therefore the rocker 117, move into their aforesaid lower positions, then the shoulder 215 on the rod 211 moves into position to be engaged by the shoulder 217 on the cam 126. Then in the course of rotation of the cam shaft 122 the interengagement of these shoulders causes the plate 203 to be pivoted about its pivotal mounting 204 and thereupon, as in the case when the lever 207 is rocked, the shoulder 202 is withdrawn from engagement with the shoulder 201 and thereupon the associated parts attain the position shown in Fig. 17 and, as explained hereinabove, the nose 184 is withdrawn from the notch 186 to disconnect the shaft 53 from the driving pulley 57 and thereby interrupt operation of the machine.

It has been explained hereinabove that the present machine is so arranged that three impressions are made on each sheet fed into printing position beneath the platen P and that to this end the stop fingers 167, 172 and 178 are successively lowered and withdrawn from sheet stopping position to dispose spaced positions on the sheet beneath the platen to receive impressions. Hence, since the stop fingers 167, 172 and 178 are respectively controlled by the cams 171, 176 and 177 included on the cam shaft 135, it is necessary that the cam shaft 135 make one revolution to three of the drive shaft 52 in order that the aforesaid impressions will be made on each sheet for the platen P is lowered into printing position once for each revolution of the drive shaft 52. Furthermore, as has been explained hereinabove, it is desirable that latching engagement of the lug 89, Fig. 3, with the shoulder 89 be assured as each sheet passes through the machine, and to this end the cam 137, Fig. 3, is mounted on the cam shaft 135, as explained hereinabove, so that the rise on the cam 137 en-

gages the cam follower 138 as the cam shaft 135 returns to its at rest position near the end of a complete rotation thereof. In addition to the foregoing, it is desirable that the detecting wheel 109 be permitted to move into detecting position once for each sheet to be fed into the machine and, as explained hereinabove, this is permitted when the drop 121 on the cam 120 moves into position beneath the roller 119.

The ratio between the main drive shaft 53 and the drive shaft 52 is one-to-one and since it is desirable that the drive shaft 52 make three revolutions to one of the cam shaft 135, for the reasons explained hereinabove, and since the cam shaft 135 is to make but a single rotation for each sheet fed into the machine and since the detecting wheel 109 is to perform a detecting operation only once for each sheet, it is manifest that the cam shaft 122 should also make but a single revolution each time the drive shaft 52 and the main drive shaft 53 make three revolutions.

In view of the foregoing, a geared connection, afforded by the gear train 218, Fig. 1, is established between the drive shaft 53 and the cam shaft 122. Furthermore, since the cam shaft 122 makes one revolution to three of the drive shaft 52, a bevel gear interconnection 219, Figs. 1 and 9, is established between the cam shaft 122 and the cam shaft 135. It will be understood, however, that if, for example, but two stop fingers were provided so that it would only be necessary for the cam shaft 135 to make one revolution while the drive shaft 52 was making two revolutions, then the geared interconnection between the shaft 53 and the cam shaft 122 would be two-to-one so that a sheet detecting operation would be performed by the wheel 109 for each sheet fed into the machine and also so that the cam shaft 135 would be operated to effect a restoring operation in so far as the lug 89 and shoulder 89' are concerned for each sheet fed into the machine. Of course, if but a single impression was to be made on each sheet, then the cam shaft 122 and therefore the cam shaft 135 would be driven in a one-to-one ratio with the shafts 52 and 53. Furthermore, if four or more impressions were to be made on each sheet, then the ratio between the drive shaft 53 and the cam shaft 122 and therefore the cam shaft 135 would be four-to-one or more depending upon the number of impressions to be made on each sheet. It will also be understood that the means for operating the sheet withdrawing means, including the suction nozzle as 40, are operated from or in timed relation with the cam shaft 122 so that a sheet withdrawing operation and the feeding of a sheet by the feed rollers as 41 into the bite between the rollers 109 and 112 will only be effected when the detecting wheel 109 will be freed, as above described, so as to perform a detecting operation.

It will be seen from the foregoing description that in the present machine each sheet fed into the machine has three impressions made thereon from a printing device disposed in printing position. It will also be understood that a printing device remains in printing position until such time as the detecting wheel 109 moves into the groove 111 under the circumstances hereinabove described so as to thereby bring about energization of the solenoid 97 and the releasing of the lug 89 from the shoulder 89'. It is assured that a sheet feeding operation will not be brought about under other circumstances by reason of

the restoring or maintaining operation effected by the cam 137 through the link 146 as an incident to passage of each sheet through the machine.

When, however, as explained hereinabove, the wheel 109 moves into the groove 111 and the solenoid 97 is consequently energized, the shoulder 202 is withdrawn from the shoulder 201 so as to move the arcuate arm 107 into position to engage the tail 199 of the dog 183 and thereby interrupt rotation of the main drive shaft 53. This serves to interrupt operation of the machine since the various operative mechanisms in the machine are driven from this main drive shaft 53. Hence, each time a detecting operation is effected by the wheel 109 by reason of the movement of this wheel into the groove 111 in the wheel 112, an advancing movement is imparted to the printing devices and operation of the machine is interrupted.

It will be understood that if the detecting wheel 109 moves into the groove 111, as aforesaid, by reason of the passage thereof through an opening as 108 in a special sheet as SP at the time interruption of operation of the machine occurs, as explained hereinabove, the special sheet SP will be engaged with the stop finger 167. It is intended that an advancing movement is to be imparted to the printing or like devices and operation of the machine is to be interrupted only when a special sheet as SP moves into position beneath the detecting wheel 109. Hence, if the detecting wheel 109 moves into the groove 111 by reason of the fact that a sheet has not been fed into the bite between the detecting wheel 109 and the wheel 112, then when interruption of the machine subsequently occurs, the operator may readily ascertain that the machine operation was interrupted by reason of improper operation of the machine for at this time no sheet will be engaged with the stop finger 167, a fact which may be readily ascertained by the operator. This affords the operator an opportunity to correct the cause of such improper operation of the machine and prevents the accrual of improper machine operation which might arise if a printing device were withdrawn from printing position above the anvil A prematurely by reason of the fact that no sheet had been fed into the bite between the wheels 109 and 112.

By way of explaining the operation of the present machine, reference can be conveniently made to the preparation of business instruments in accordance with the disclosure of the above referred to application of Harold M. Whittlesey, Serial No. 403,357, filed July 21, 1941, where it is explained that all business instruments that are to receive identical variable data as, for example, the amounts to be billed the customers of a public utility are grouped, which is to say, in accordance with the disclosure of the aforesaid Whittlesey application, all public utility bills, for example, to go to customers that are to be billed under the same rate schedule for consumption of an identical quantity of the commodity distributed by the public utility are arranged in a group. In the present instance, such groups are separated by arranging between the last bill in one group and the first bill in a succeeding group a special sheet such as is identified herein as SP.

In an instance such as the foregoing the printing devices that are to be stacked in the magazine M and which are to be advanced to printing position are arranged, for example, to have type

characters included thereon from which a consumption quantity, the amount of a gross bill and the amount of a net bill may be printed, the amount of the gross bill and the net bill being determined by the rate or rate schedule at which a charge is to be made, the consumption quantity being multiplied by such rate. These printing devices are then arranged in a predetermined order as, for example, so that the consumption quantities of from one up to any desired quantity, for example, three hundred, are arranged in numerical sequence.

With the printing devices arranged in this manner, the bills that are to be printed in the machine are arranged in the rack 39 so that all of the bills that are to be billed for a consumption quantity of one will first be withdrawn from the rack 39 followed by all those which are to be billed for a consumption quantity of two, three, four and so on, these different groups of bills having interposed therebetween, as explained hereinabove, a special sheet such as that identified herein as SP.

When the machine is first set in operation, after a quantity of printing devices have been stored in the magazine M, the machine is manually operated under control of the handle 195 until the first printing device in the series is advanced into printing position above the anvil A. Then the machine is set in automatic operation by causing the shoulder 201 to be engaged with the shoulder 202 and by this time a sheet will be disposed in engagement with the first stop finger 167. In the illustrated machine, in the course of the first revolution of the drive shaft 52 the platen P will make an impression on the sheet from the printing device disposed in printing position and thereafter the stop finger 167 will elevate and the sheet will be advanced by the tapes T so that the leading edge thereof is engaged with the stop finger 172. Then during the second revolution of the shaft 52, the second impression will be made on the sheet and subsequently the stop finger 172 will be elevated and the leading edge of the sheet will advance into engagement with the stop finger 178. In the course of the third revolution of the shaft 52 the third impression will be made on the sheet S and while this is being done, the sheet feeding means, as for example, the nozzles as 40 and the rollers as 41, will be advancing the succeeding sheet beneath the detecting wheel 109. After the third impression has been made on the first sheet in the course of the third revolution of the shaft 52, the stop finger 178 will raise to free the first sheet which will thereupon pass into the sheet collector K, and the stop finger 167 will return to sheet stopping position so that by the time the second sheet has passed under the wheel 109 and been advanced so that the leading edge thereof engages the stop finger 167, a detecting operation will have been performed by the wheel 109.

The machine will continue in operation, as above described, and during the fourth revolution of the shaft 52 an operation like that which occurred during the first revolution thereof will take place and during the fifth revolution of the shaft 52, an operation like that occurring in the second revolution thereof will occur and so on. The machine will continue to operate in this manner until during a time when the leading edge of a sheet is engaged with the stop finger 178, which will correspond to the hereinabove described third revolution of the shaft 52, a spe-

cial sheet SP moves into position beneath the detecting wheel 109.

When a special sheet SP moves into position beneath the detecting wheel 109 at a time such as that just described, the detecting wheel passes through the opening as 108 into the groove 111 and thereupon the contact point 126 is engaged with the contact point 127 to bring about energization of the solenoid 97. This operation will occur immediately after the platen P has made the third impression on a sheet disposed therebelow and at this time the arm 77 of the rocker 73 will be approaching the position in which it is shown in Figs. 6 and 7. Hence, if the solenoid 97 is energized at this time, the rocker 85 will be freed to the effect of the spring 94 and will move into the position shown in Fig. 7 to thereby withdraw the finger 88 from the position in which it can engage the pawl 78 in the manner shown in Fig. 6. It will be understood that in each operation of the machine up and until the time the solenoid 97 is energized, as just described, the rocker 85 has been maintained in its latched position so that the finger 88 functioned to prevent the driving member, as the pawl 78, from engaging the driven member, as the pin 82, and therefore no advancing movement has been imparted to the printing devices.

However, when the solenoid 97 is energized and the rocker 85 is unlatched, as aforesaid, the driving member, as the pawl 78, moves into engagement with the adjacent pin 82 in the manner shown in Fig. 7 and during the latter part of the ensuing revolution of the shaft 52 the arm 77 of the rocker 73 moves from the position in which it is shown in Figs. 6 and 7 back into the position in which it is shown in Fig. 3. In the course of this return movement an advancing movement is imparted to the printing devices so that the printing device which has been disposed on the anvil A is passed out through the discharge chute C into the galley G and the succeeding printing device is moved into position above the anvil A.

By comparing Figs. 3 and 7 it will be seen that a short time after the arm 77 of the rocker 73 moves from the position in which it is shown in Fig. 7 toward the position in which it is shown in Fig. 3, the pawl 78 is advanced from the position in which it can be engaged by the finger 88, and it is after the time that the pawl 78 has advanced from the position in which it can be engaged by the finger 88 that the rise on the cam 137 cooperates with the roller 128 to effect the hereinabove described restoring movement of the rocker 85. Hence, by the time the pawl 78 attains its normal at rest position, in which it is shown in Fig. 3, the lug 89 is restored to latching engagement with the shoulder 89' in the manner shown in Fig. 3. It will be understood that this assurance that the lug 89 is latched on the shoulder 89' occurs at a time corresponding to that described above in each rotation of the cam shaft 135, and this insures against an undesired advancing movement being imparted to the printing devices.

As has been explained hereinabove, movement of the detecting wheel 109 into the groove 111 not only results in energization of the solenoid 97 but also causes the shoulder 215, Fig. 9, on the rod 211 to be engaged by the shoulder 217 on the arm 216 so that the plate 203 is pivoted and the shoulder 202 is withdrawn from engagement with the shoulder 201 to thereby free the shaft 193 and

the parts carried thereby to the effect of the spring 196. This permits the arcuate arm 181 to move into position to engage the tail 199 of the dog 183. This, however, does not occur until the shaft 52 has rotated in an amount sufficient to bring the arm 11 of the rocker 13 and the pawl 18 substantially into the positions in which these parts are shown in Fig. 3, but shortly prior to the time that these parts attain these positions the tail 199 engages the inner arcuate surface of the arm 181 with the result that by the time the arm 11 and pawl 18 have attained the position shown in Fig. 3, the nose 184 will be withdrawn from the notch 186 and machine operation will be interrupted, as hereinabove described.

If at the time operation of the machine is interrupted in the manner just described a special sheet as SP is engaged with the stop finger 167, which can be readily ascertained by the machine operator, then the operator grasps the handle 195 and retracts it from the position shown in Fig. 12, into which it will have moved, and restores it to the position in which it is shown in Fig. 9. Thereupon the arcuate arm 181 is withdrawn from engagement with the tail 199 of the dog 183 and the nose 184 reenters the notch 186 and the machine operation is resumed, and impressions are now made from the printing device that has been advanced into printing position until another sheet as SP is encountered, at which time machine operation will be interrupted and advancing of the printing devices will be brought about in the manner hereinabove described. It will be recognized that there may be instances where special sheets as SP will successively pass through the machine, and if this occurs machine operation will be interrupted as soon as the cam shafts 122 and 135 have completed a single revolution, during which time of course the main drive shaft 53 and the drive shaft 52 will make three revolutions in the illustrated form of the machine.

In the event a sheet should fail to advance into the bite between the detecting wheel 109 and the wheel 112, an advancing movement will be imparted to the printing devices and operation of the machine will be interrupted in the manner hereinabove described. However, before again setting the machine in operation the operator will ascertain that a sheet has not been advanced into engagement with the stop finger 167. Hence the operator is afforded the opportunity of ascertaining the reason a sheet failed to feed and for correcting the circumstance which brought this about. Moreover, this gives the operator an opportunity to prevent improper impressions from being made on the sheets remaining in the rack 39 in advance of the next succeeding special card as SP. The operator may either remove the sheets in advance of the special card as SP and the printing device which will have newly advanced into the gallery G to enable these sheets to be printed from this particular printing device at the end of the run of printing devices and sheets being made in the machine, or the operator may proceed in other ways to insure that these sheets will receive impressions from this particular printing device.

There may be instances where it will be desirable that a driving member as the pawl 18 engage a driven member as the pawl 82 each time an operating member as the rocker 13 is set in operation and in such instances the finger as 88 on the rocker 85 is to be prevented from engaging the pawl as 18 so as to prevent engagement there-

of with the driven member as the pawl 82. This may be expeditiously accomplished by preventing latching of the lug 89 on the shoulder 89', and to enable this to be accomplished the spring anchor 105 may be disconnected from the pin 107. It is to this end that the relatively enlarged opening 106 is provided in the spring anchor 105, for this facilitates disengagement of the spring anchor 105 from the pin 107. When the spring anchor is detached in the manner just described, the spring 104 is relieved of tension and consequently the arm 91 bearing the shoulder 89' drops from position in which the shoulder can engage the lug 89 and latch the arm 85 in such position that the finger 88 may engage the driving member as the pawl 18, the finger 88 and the rocker 85 in such an instance being disposed in what may well be called an inoperative position.

Of course, in such an instance the detecting wheel 109 will still perform the above described sheet detecting operation and in the event a sheet fails to feed at a time when this should occur, operation of the machine will be interrupted in the manner above described, and this may also bring about energization of the solenoid 97, but inasmuch as the lug 89 will not be latched on the shoulder 89', such energization of the solenoid 97 will be ineffective, but the interruption of operation of the machine, as a result of sheet detection, will still be effective.

It will be manifest from the foregoing description that I have provided a printing machine wherein advancing movement of the printing devices is brought about under control of sheets fed through the machine and it will be appreciated that, as explained hereinabove, the arrangement is such that assurance against improper operation of the machine is afforded for, in addition to controlling the advance of the printing devices into printing position under control of these sheets, I have also so arranged the machine that operation thereof will be interrupted in event a sheet is not fed into the machine at a time when this should occur. This is accomplished by causing operation of the machine as a whole to be interrupted each time when advancing movement is imparted to the printing devices for so to do enables the operator of the machine to readily ascertain an improper machine operation.

Many other and further advantages of the present invention will be apparent to those skilled in the art and thus while I have illustrated and described a selected embodiment of my invention, it is to be understood that this is capable of variation and modification and I therefore do not wish to be limited to the precise details set forth but desire to avail myself of such changes and alterations as fall within the purview of the following claims.

I claim:

1. In a printing machine through which groups of sheets, each comprising one or more sheets and in which groups one sheet has characteristics incorporated therein effective to distinguish it from any other sheet in the group, are fed seriatim to have impressions made on the sheets, means for feeding the groups of sheets and the sheets in the groups thereof seriatim to a printing position in the machine, means for advancing printing devices seriatim to said printing position, normally ineffective means for operating said advancing means and operative when effective to operate said advancing means to dispose a printing device in printing position, detecting means adapted for cooperation with the sheets,

one at a time and means controlled by the detecting means for rendering the normally ineffective means effective to operate the advancing means upon cooperation of said detecting means with a sheet in a group thereof embodying characteristics distinguishing such sheet from any other sheet in the group in which such sheet is included whereby a different printing device is disposed at the printing position for each group of sheets fed to such position.

2. In a printing machine through which groups of sheets, each comprising one or more sheets and in which groups one sheet has characteristics incorporated therein effective to distinguish it from any other sheet in the group, are fed seriatim to have impressions made on the sheets, means for feeding the groups of sheets and the sheets in the groups thereof seriatim to a printing position in the machine, means for advancing printing devices seriatim to said printing position, normally ineffective means for operating said advancing means and operative when effective to operate said advancing means to dispose a printing device in printing position, detecting means adapted for cooperation with the sheets one at a time and responsive to characteristics incorporated in a sheet in a group thereof to distinguish such sheet from any other in the group in which it is included, means for effecting cooperation of the detecting means with each sheet fed into the machine, control means that are rendered operative upon cooperation of the detecting means with a sheet bearing distinguishing characteristics, as aforesaid, and upon response of said detecting means to such characteristics in such sheet, and means controlled by the control means and which are rendered effective when the control means are rendered operative for rendering the normal ineffective means effective to operate the advancing means to thereby advance a printing device to printing position whereby a different printing device is disposed at the printing position for each group of sheets fed to such position.

3. In a printing machine through which groups of sheets, each comprising one or more sheets and in which groups one sheet has characteristics incorporated therein effective to distinguish it from any other sheet in the group, are fed seriatim to have impressions made on the sheets, means for moving the sheets seriatim to a printing position in the machine, means for advancing printing devices seriatim to said printing position, normally ineffective means for operating said advancing means and operative when effective to operate said advancing means to dispose a printing device in printing position, detecting means adapted for cooperation with the sheets one at a time, means controlled by the detecting means for rendering the normally ineffective means effective to operate the advancing means upon cooperation of said detecting means with a sheet in a group thereof embodying characteristics distinguishing such sheet from any other sheet in the group in which such sheet is included whereby a different printing device is disposed at the printing position for each group of sheets fed to such position, means for releasably retaining a sheet in the printing position, means for feeding sheets to the sheet moving means, control means for rendering the retaining means effective to retain a sheet in printing position and for rendering the means for feeding sheets to the sheet moving means inoperative each time a sheet bearing characteristics dis-

tinguishing it from any other sheet in the group in which it is included is fed to printing position, and means for rendering the control means ineffective to thereby cause the retaining means to release the sheet retained thereby, the last-named means also being effective to render the sheet feeding means operative to feed another sheet to the sheet moving means.

4. In a printing machine through which groups of sheets, each comprising one or more sheets and in which groups one sheet has characteristics incorporated therein effective to distinguish it from any other sheet in the group, are fed seriatim to have impressions made on the sheets, means for moving the sheets seriatim to a printing position in the machine, means for advancing printing devices seriatim to said printing position, normally ineffective means for operating said advancing means and operative when effective to operate said advancing means to dispose a printing device in printing position, detecting means adapted for cooperation with the sheets one at a time, means controlled by the detecting means for rendering the normally ineffective means effective to operate the advancing means upon cooperation of said detecting means with a sheet in a group thereof embodying characteristics distinguishing such sheet from any other sheet in the group in which such sheet is included whereby a different printing device is disposed at the printing position for each group of sheets fed to such position, means for releasably retaining a sheet in the printing position, means for feeding sheets to the sheet moving means, control means that are rendered operative upon cooperation of the detecting means with a sheet bearing distinguishing characteristics, as aforesaid, and upon response of said detecting means to such characteristics in a sheet and which control means are effective when rendered operative to render the retaining means effective to retain a sheet in printing position and also to render the means for feeding sheets to the sheet moving means inoperative whereby each sheet bearing characteristics distinguishing it from any other sheet in the group in which it is included is retained in printing position, and manually operable means for rendering the control means ineffective to thereby cause the retaining means to release the sheet retained thereby, the last-named means also being effective to render the sheet feeding means operative to feed another sheet to the sheet moving means.

5. In a printing machine through which groups of sheets, each comprising one or more sheets and in which groups one sheet has characteristics incorporated therein effective to distinguish it from any other sheet in the group, are fed seriatim to have impressions made on the sheets, means for feeding the groups of sheets and the sheets in the groups thereof seriatim to a printing position in the machine, means for advancing printing devices seriatim to said printing position, normally ineffective means for operating said advancing means and operative when effective to operate said advancing means to dispose a printing device in printing position, impression producing means at printing position, operating means for causing the impression producing means to make impressions from the printing devices disposed at printing position onto sheets fed to such position, detecting means adapted for cooperation with the sheets one at a time, means controlled by the detecting means

for rendering the normally ineffective means effective to operate the advancing means upon cooperation of said detecting means with a sheet in a group thereof embodying characteristics distinguishing such sheet from any other sheet in the group in which such sheet is included whereby a different printing device is disposed at the printing position for each group of sheets fed to such position, means for retaining a sheet in printing position while the impression producing means is effective thereon and operative to release said sheet after an impression has been made thereon, control means effective to prevent release of a sheet by the retaining means and also effective to interrupt operation of the impression producing means and the means for feeding sheets into the machine each time a sheet bearing characteristics distinguishing it from any other sheet in the group in which it is included is fed to printing position, and means for rendering the control means ineffective to thereby cause the retaining means to release the sheet retained thereby, the last-named means also being effective to render the impression producing means operative as well as the sheet feeding means whereby impressions are made on sheets fed into the machine from the printing device disposed at printing position until said control means is again rendered effective.

6. In a printing machine through which groups of sheets, each comprising one or more sheets and in which groups one sheet has characteristics incorporated therein effective to distinguish it from any other sheet in the group, are fed seriatim to have impressions made on the sheets, means for feeding the groups of sheets and the sheets in the groups thereof seriatim to a printing position in the machine, means for advancing printing devices seriatim to said printing position, normally ineffective means for operating said advancing means and operative when effective to operate said advancing means to dispose a printing device in printing position, impression producing means at printing position, operating means for causing the impression producing means to make impressions from the printing devices disposed at printing position onto sheets fed to such position, detecting means adapted for cooperation with the sheets one at a time, means controlled by the detecting means for rendering the normally ineffective means effective to operate the advancing means upon cooperation of said detecting means with a sheet in a group thereof embodying characteristics distinguishing such sheet from any other sheet in the group in which such sheet is included whereby a different printing device is disposed at the printing position for each group of sheets fed to such position, means for retaining a sheet in printing position while the impression producing means is effective thereon and operative to release said sheet after an impression has been made thereon, control means that are rendered operative upon cooperation of the detecting means with a sheet bearing distinguishing characteristics, as aforesaid, and upon response of said detecting means to such characteristics in such sheet and which control means are effective when rendered operative to render the retaining means effective to retain a sheet in printing position and to also render the impression producing means and the means for feeding sheets into the machine inoperative whereby each sheet bearing characteristics distinguishing it from any other sheet in the group in which it is included

is retained in printing position, and manually operable means for rendering the control means ineffective to thereby cause the retaining means to release the sheet retained thereby, the last-named means also being effective to render the impression producing means and the sheet feeding means operative to thereby bring about the feeding of further sheets into the machine and the production of impressions thereon.

7. In a printing machine through which groups of sheets each comprising one or more sheets and in which groups one sheet has characteristics incorporated therein effective to distinguish it from any other sheet in the group, are fed seriatim to have impressions made on the sheets, means for feeding the groups of sheets and the sheets in the groups thereof seriatim to a printing position in the machine, means for advancing printing devices seriatim to said printing position, driving means for said advancing means, means for latching said driving means in ineffective position, detecting means adapted for cooperation with the sheets one at a time, means controlled by the detecting means for releasing the latching means to thereby render the driving means effective to operate the advancing means upon cooperation of said detecting means with a sheet in a group thereof embodying characteristics distinguishing such sheet from any other sheet in the group in which such sheet is included whereby a different printing device is disposed at the printing position for each group of sheets fed to such position, and means effective to restore or insure latching of said latching means as an incident to the feeding of each sheet through the machine.

8. In a printing machine through which groups of sheets each comprising one or more sheets and in which groups one sheet has characteristics incorporated therein effective to distinguish it from any other sheet in the group, are fed seriatim to have impressions made on the sheets, means for moving the sheets seriatim to printing position in the machine, means for advancing printing devices seriatim to said printing position, driving means for said advancing means, means for latching said driving means in ineffective position, detecting means adapted for cooperation with the sheets one at a time, means controlled by the detecting means for releasing the latching means to thereby render the driving means effective to operate the advancing means upon cooperation of said detecting means with a sheet in a group thereof embodying characteristics distinguishing such sheet from any other sheet in the group in which such sheet is included whereby a different printing device is disposed at the printing position for each group of sheets fed to such position, means effective to restore or insure latching of said latching means as an incident to the feeding of each sheet through the machine, means for releasably retaining a sheet in the printing position, means for feeding sheets to the sheet moving means, control means for rendering the retaining means effective to retain a sheet in printing position and for rendering the means for feeding sheets to the sheet moving means inoperative each time a sheet bearing characteristics distinguishing it from any other sheet in the group in which it is included is fed to printing position, and means for rendering the control means ineffective to thereby cause the retaining means to release the sheet retained thereby, the last-named means also being effective to render the sheet feeding

means operative to feed another sheet to the sheet moving means.

9. In a printing machine through which groups of sheets each comprising one or more sheets and in which groups one sheet has characteristics incorporated therein effective to distinguish it from any other sheet in the group, are fed seriatim to have impressions made on the sheets, means for moving the sheets seriatim to printing position in the machine, means for advancing printing devices seriatim to said printing position, driving means for said advancing means, means for latching said driving means in ineffective position, detecting means adapted for cooperation with the sheets one at a time, means controlled by the detecting means for releasing the latching means to thereby render the driving means effective to operate the advancing means upon cooperation of said detecting means with a sheet in a group thereof embodying characteristics distinguishing such sheet from any other sheet in the group in which such sheet is included whereby a different printing device is disposed at the printing position for each group of sheets fed to such position, means effective to restore or insure latching of said latching means as an incident to the feeding of each sheet through the machine, means for releasably retaining a sheet in the printing position, means for feeding sheets to the sheet moving means, control means that are rendered operative upon cooperation of the detecting means with a sheet bearing distinguishing characteristics, as aforesaid, and upon response of said detecting means to such characteristics in a sheet and which control means are effective when rendered operative to render the retaining means to retain a sheet in printing position and also to render the means for feeding sheets to the sheet moving means inoperative whereby each sheet bearing characteristics distinguishing it from any other sheet in the group in which it is included is retained in printing position, and manually operable means for rendering the control means ineffective to thereby cause the retaining means to release the sheet retained thereby, the last-named means also being effective to render the sheet feeding means operative to feed another sheet to the sheet moving means.

10. In a printing machine through which sheets, at least selected of which bear distinguishing characteristics, are fed seriatim to have impressions made on the sheet, means for feeding the sheets seriatim to a printing position in the machine, means for advancing printing devices seriatim to said printing position and including a driven member and a driving member means for preventing interconnection of said driven and said driving members and including a normally engaged latch, detecting means adapted for cooperation with the sheets, means controlled by the detecting means for releasing the latch to thereby render the driving member effective to operate the driven member upon cooperation of the detecting means with a sheet bearing distinguishing characteristics whereby the advancing means operates to advance a printing device into printing position each time a sheet bearing distinguishing characteristics is moved into cooperation with the detecting means, and means effective to restore or insure latching of said latch as an incident to the feeding of each sheet through the machine.

11. In a printing machine through which sheets, at least selected of which bear distin-

guishing characteristics, are fed seriatim to have impressions made on the sheets, means for moving sheets to a printing position in the machine, means for advancing printing devices seriatim to said printing position and including a driving member and a driven member, means for rendering said driving member ineffective to drive said driven member and including a normally engaged latching means, means for feeding sheets to the sheet moving means, detecting means adapted for cooperation with the sheets, means controlled by the detecting means for interrupting operation of the sheet feeding means upon cooperation of the detecting means with a sheet bearing distinguishing characteristics, other means controlled by the detecting means for releasing the latching means to thereby render the driving member effective to drive the driven member upon cooperation of the detecting means with a sheet bearing distinguishing characteristics whereby the advancing means operates to advance a printing device into printing position each time a sheet bearing distinguishing characteristics is moved into cooperation with the detecting means, and means effective to restore or insure latching of said latching means as an incident to the feeding of each sheet through the machine.

12. In a printing machine through which groups of sheets each comprising one or more sheets and in which groups one sheet has characteristics incorporated therein effective to distinguish it from any other sheet in the group, are fed seriatim to have impressions made on the sheets, means for moving the sheets seriatim to printing position in the machine, means for advancing printing devices seriatim to said printing position, driving means for said advancing means, means for latching said driving means in ineffective position, detecting means adapted for cooperation with the sheets one at a time, means controlled by the detecting means for releasing the latching means to thereby render the driving means effective to operate the advancing means upon cooperation of said detecting means with a sheet in a group thereof embodying characteristics distinguishing such sheet from any other sheet in the group in which such sheet is included whereby a different printing device is disposed at the printing position for each group of sheets fed to such position, means effective to restore or insure latching of said latching means as an incident to the feeding of each sheet through the machine, means for releasably retaining a sheet in the printing position, means for feeding sheets to the sheet moving means, control means for rendering the retaining means effective to retain a sheet in printing position and for rendering the means for feeding sheets in the sheet moving means inoperative each time a sheet bearing characteristics distinguishing it from any other sheet in the group in which it is included is fed to printing position, means for rendering the control means ineffective to thereby cause the retaining means to release the sheet retained thereby, the last-named means also being effective to render the sheet feeding means operative to feed another sheet to the sheet moving means, means for operating the means for feeding sheets to the sheet moving means and the detecting means in timed relation so that the detecting means is caused to cooperate with each sheet fed to the sheet moving means, and means controlled by the detecting means and effective to interrupt operation of the machine in each instance where a

sheet is not fed to the sheet moving means by the means for feeding sheets thereto.

13. In a printing machine through which groups of sheets, each comprising one or more sheets and in which groups one sheet has characteristics incorporated therein effective to distinguish it from any other sheet in the group, are fed seriatim to have impressions made on the sheets, means for moving the sheets seriatim to a printing position in the machine, means for advancing printing devices seriatim to said printing position, normally ineffective means for operating said advancing means and operative when effective to operate said advancing means to dispose a printing device in printing position, detecting means adapted for cooperation with the sheets one at a time, means controlled by the detecting means for rendering the normally ineffective means effective to operate the advancing means upon cooperation of said detecting means with a sheet in a group thereof embodying characteristics distinguishing such sheet from any other sheet in the group in which such sheet is included whereby a different printing device is disposed at the printing position for each group of sheets fed to such position, means for releasably retaining a sheet in the printing position, means for feeding sheets to the sheet moving means, control means that are rendered operative upon cooperation of the detecting means with a sheet bearing distinguishing characteristics, as aforesaid, and upon response of said detecting means to such characteristics in a sheet and which control means are effective when rendered operative to render the retaining means to retain a sheet in printing position and also to render the means for feeding sheets to the sheet moving means inoperative whereby each sheet bearing characteristics distinguishing it from any other sheet in the group in which it is included is retained in printing position, manually operable means for rendering the control means ineffective to thereby cause the retaining means to release the sheet retained thereby, the last-named means also being effective to render the sheet feeding means operative to feed another sheet to the sheet moving means, means for operating the means for feeding sheets to the sheet moving means and the detecting means in timed relation so that the detecting means is caused to cooperate with each sheet fed to the sheet moving means, and means controlled by the detecting means and effective to interrupt operation of the machine in each instance where a sheet is not fed to the sheet moving means by the means for feeding sheets thereto.

14. In a printing machine through which groups of sheets, each comprising one or more sheets and in which groups one sheet has characteristics incorporated therein effective to distinguish it from any other sheet in the group, are fed seriatim

to have impressions made on the sheets, means for feeding the groups of sheets and the sheets in the group thereof seriatim to the machine, means for moving sheets fed to the machine to a printing position in the machine, means for advancing printing devices seriatim to said printing position, normally ineffective means for operating said advancing means and operative when effective to operate said advancing means to dispose a printing device in printing position, means for retaining a sheet against movement with the sheet moving means, operating means effective to dispose the retaining means in sheet retaining position and also effective to retract such means from sheet retaining position, detecting means disposed for cooperation with the sheet after feeding thereof to the sheets one at a time moving means by the sheet feeding means and prior to advancing thereof to the retaining means, means for operating the detecting means and the sheet feeding means in timed relation one with the other and effective to cause the detecting means to cooperate with each sheet fed to the machine by the sheet feeding means, control means controlled by the detecting means and effective each time the sheet feeding means fails to feed into cooperating relation with the detecting means for interrupting operation of the sheet feeding means, the operating means for the retaining means and the means for operating the detecting means and the sheet feeding means in timed relation one with the other whereby the retaining means is retained in sheet retaining position without having a sheet in engagement therewith, means controlled by the detecting means for rendering the normally ineffective means effective to operate the advancing means upon cooperation of the detecting means with a sheet in a group thereof embodying characteristics distinguishing such sheet from any other sheet in the group in which such sheet is included whereby a different printing device is disposed at printing position for each group of sheets fed to such position, said control means being effective upon cooperation of the detecting means with a sheet bearing distinguishing characteristics, as aforesaid, to interrupt operation of the sheet feeding means, the operating means for the retaining means and the means for operating the detecting means and the sheet feeding means in timed relation one with the other whereby the retaining means is retained in sheet retaining position with a sheet bearing distinguishing characteristics, as aforesaid, in engagement therewith, and means for rendering the control means ineffective to thereby set in operation the sheet feeding means, the operating means for the retaining means, and the means for operating the sheet feeding means and the detecting means in timed relation.

FRANKLIN E. CURTIS.
